UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

MINING MACHINE.

Application filed August 31, 1925. Serial No. 53,725.

This invention relates to mining machines and more particularly to mining machines of the laterally fed continuous cutter type.

The primary object of this invention is to provide a mining machine of the flexibly fed continuous cutter type having improved mechanism for feeding the machine, for actuating the cutter chain, and for moving the machine about the mine when arranged on its transport truck. Another object of this invention is to provide improved mechanism whereby the machine may be fed at a plurality of speeds, namely, a fast moving or positioning speed, an intermediate summing speed, and a slow cutting speed. These and other objects of my invention will, however, subsequently appear.

This invention may be embodied in a machine comprising a frame slidable on its bottom on the mine bottom and having projecting forwardly therefrom a rigid cutter bar on which a cutter bit carrying cutter chain is supported. A driving motor preferably is mounted on the frame and has a longitudinally extending armature shaft on the opposite ends of which pinions are rigidly secured. The forward motor pinion is adapted to actuate through improved transmission means a plurality of feed operating and controlling members with which flexible feeding members cooperate, one of the flexible feeding members forming an advance portion which is anchored at its free end at the advancing side of the machine while the other portion is anchored at its free end at the receding side of the machine. The rear motor pinion may actuate, through an improved transmission means, the cutter chain and the truck driving mechanism.

In the accompanying drawings I have shown for purposes of illustration one form which my invention may assume in practice.

In these drawings,—

Fig. 1 is a plan view of a mining machine constructed in accordance with one embodiment of the invention, a portion of the cutting and feeding mechanism being shown in horizontal section.

Fig. 2 is a central vertical longitudinal sectional view taken substantially on line 2—2 of Fig. 1, parts being shown in elevation.

Fig. 3 is a front end elevational view of the machine shown in Figs. 1 and 2.

Fig. 4 is a detail transverse horizontal

sectional view taken substantially on line 4—4 of Fig. 2.

In this illustrative construction I have shown a mining machine of the flexibly fed continuous cutter room and pillar type 60 designated as an entirety by the reference character 1 having a frame 2 slidable on its bottom 3 on the mine bottom, or invertible to slide on its plane upper surface 3^a. The frame 2 comprises a bed section 4, a motor section 5, a feed section 6, and a section 7 which houses the truck driving mechanism and a portion of the actuating means for the cutter chain, the sections 5, 6, and 7 being mounted upon the bed section 4 and rigidly 65 secured thereto in any approved manner. As shown, the motor section 5 is interposed between the sections 6 and 7. Housed within the motor section 5 is a motor 8, herein of the reversible electric type, having a longitudinally extending horizontal armature shaft 9.

Specifically noting the actuating mechanism for the cutter chain and the truck driving member, it will herein be observed 80 that suitably secured to the rear end of the armature shaft 9 is a spur motor pinion 10 which meshes with a spur gear 11 secured to a shaft 12 disposed parallel with the armature shaft. As illustrated, the shaft 12 is journaled within a bearing 13 carried by the machine frame and has secured thereto at its rear end a bevel pinion 14 which meshes with a large bevel gear 15 splined as at 16 to a vertically disposed shaft 17 85 journaled at its opposite ends in ball bearings 18 and 19 carried by the machine frame. Arranged coaxially with the shaft 17 and journaled on a bearing sleeve 20 is a driving sprocket 21 which cooperates with the cutter bit carrying cutter chain 22 to drive the latter in a well known manner. The cutter chain 22 is supported on a rigid cutter bar 23 which projects forwardly from the bed section 4. Furthermore, splined as at 24 to the shaft 17 is a reciprocable clutch member 26 having formed thereon at its lower end clutch teeth 27 which are adapted to cooperate with clutch teeth 27^a formed in the hub of the driving sprocket 21. Cooperating 100 with the clutch member 26 is a clutch shipper 28 suitably secured to a transversely disposed actuating shaft 29 journaled as at 30 within the frame section 7 and this shaft has secured thereto at one end thereof a 105

Fig. 4 is a detail transverse horizontal

worm rack 31 with which a worm 32 is meshed, the latter being secured to a longitudinally extending shaft 33 which carries an operating member 34. It will thus be evident that when the operating member 34 is actuated by the operator the cutter chain driving sprocket 21 may be connected in operative driving relation with the shaft 17 or remain stationary at will while the motor 8 continuously operates. It will further be observed that meshing with the bevel gear 15 is a bevel pinion 35 splined as at 36 to a longitudinally extending horizontal shaft 37 journaled in ball bearings 38 carried by the machine frame and this shaft has suitably secured thereto an internally toothed truck driving member 39 which is adapted to drive the transport truck (not shown) in a well known manner. It will herein be noted that the opposite sides of the frame section 7 are provided with chambers 40 and 41 within which suitable controller and rheostat devices are adapted to be housed.

In specifically describing the improved feeding mechanism it will herein be observed that suitably secured to the forward end of the armature shaft 9 is a spur motor pinion 42 which meshes with a spur gear 43 suitably secured to a longitudinally extending horizontal shaft 44 journaled in ball bearings 45 carried by a bracket 46 carried by the bed section 4. As shown, the shaft 44 has secured thereto a bevel pinion 47 which meshes with a large bevel gear 48 splined as at 49 to a vertically disposed shaft 50 journaled at 51 and 52 within the frame sections 4 and 6, respectively. Furthermore, splined at 53 to the lower end of the shaft 50 and driven by the latter is a spur gear 54 which meshes with a spur gear 55 splined at 56 to a shaft 57 disposed in front of and parallel with the shaft 50 and this shaft 57 is journaled at its upper and lower ends within ball bearings 58 and 59, respectively. As shown, splined at 60 to the upper end of the shaft 57 is a spur gear 61 which drives through an intermediate gear 62 a spur gear 64 loosely journaled on the upper end of the shaft 50 and this gear 64 is driven at a slow speed in the opposite direction from the gear 54. Rigidly secured to the shaft 57 intermediate its ends is a worm 65 while loosely journaled intermediate the ends of the shaft 50 is a worm 66, the latter being adapted to be selectively driven at different speeds in opposite directions from the gears 54 and 64 through suitable clutch mechanism. This clutch mechanism comprises clutch members 67 and 68 splined to the hubs of the gears 54 and 64, respectively, and these clutch members have clutch teeth 69 and 70, respectively, adapted to co-operate with clutch teeth 71 and 72 formed on the opposite ends of the worm 66. As shown, clutch shippers 73 and 74 are provided for the clutch members 67 and 68, re-

spectively, and these shipper members are connected together by means of a pivotally connected link 75. Herein the shipper member 73 is secured to a transversely disposed horizontal shaft 76 suitably journaled on the machine frame 2 while the shipper member 74 is splined to a transverse horizontal actuating shaft 77 journaled within bearings 78 at the opposite sides of the frame section 6. Suitably secured to the shaft 77 is a worm gear segment 79 which is meshed with a worm 80 secured to a longitudinally extending horizontal actuating shaft 81 suitably journaled on the machine frame and having at its rear end an operating member 82. It will thus be evident that when the operator suitably manipulates the operating member 82 the gears 54 and 64 may be selectively connected to the worm 66 to drive the latter at different speeds in opposite directions. It is obvious that the speed reduction between the gear 54 and the gear 64 and the inclination of the teeth on the worms 65 and 66 may be varied to suit different conditions, thereby attaining different feeding speeds.

Mesning with the worm 66 at opposite sides thereof are worm gears 83 and 84 rotating on parallel longitudinally extending horizontal axes and splined as at 85 to the hubs of bevel gears 86 and 87, while meshing with the worm 65 at opposite sides thereof are worm gears 88 and 89 arranged coaxially with the gears 83 and 84, respectively, and likewise splined as at 90 to the hubs of bevel gears 91 and 92. As illustrated, the bevel gears 86, 91 and 87, 92 are respectively journaled on longitudinally extending horizontal shafts 93 and 94, the latter in turn being journaled on the machine frame in ball bearings 95 and in sleeve members 96 later described journaled in detachable cover members 97 secured to a detachable frame section 98 forming a portion of the feed frame section 6. Mesning with the bevel gears 86, 91 and 87, 92, respectively, are planetary bevel pinions 99 and 100 journaled on radially extending stub shafts 101 supported by planet carrier members 102 splined as at 103 to the shafts 93 and 94, respectively. Herein it will be observed that splined at 104 to each of the shafts 93, 94 are clutch members 105 forming a portion of friction clutch devices generally designated 106 and 107. As these devices are substantially identical, the description of one will suffice for both. As shown, the clutch member 105 carries a series of clutch disks 108 which are interleaved with a series of clutch disks 109 carried by a clutch housing member 110, the latter being carried by the sleeve member 96 and journaled upon a bearing sleeve 111 carried by the hub of the clutch member 105 and the sleeve member 96 rotating within ball bearings 96a. Journaled on a

bearing sleeve 112 supported by each of the shafts 93 and 94 is a clutch disk retaining and housing member 113, the hub of which has slidably mounted thereon a clutch applying member 114 having projecting fingers 115 which project through apertures formed in the member 113 into engagement with certain of a series of clutch disks 108, 109. Cooperating with each of the members 114 is a shipper member 116 pivoted as at 117 on the machine frame and having formed thereon a worm rack 118 which is meshed with a worm 119 suitably secured to a longitudinally extending horizontal actuating shaft 120 suitably journaled within the machine frame and having secured thereto at its rear end an operating member 121. As illustrated, splined at 122 to the hubs of the housing members 110 are feed operating members 123 and 124 herein in the form of drums. Cooperating with the drums 123, 124, respectively, are flexible feeding members 125 and 126 herein in the form of wire ropes or cables. It will hereinafter be evident that when the operator suitably manipulates the operating members 121 the drums 123, 124 may be connected in operative driving relation with the shafts 93 and 94 or remain idle at will. It will also be evident that when the worms 65 and 66 are simultaneously rotated in the same direction, one feeding speed is obtained while if the worm 65 is rotated and the worm 66 held stationary, it being understood that the latter is self-locking, another feeding speed is obtained, and if the worms 65 and 66 are simultaneously rotated in opposite directions a third feeding speed is obtained, the rotation of the bevel gears 86 and 87 when driven by the worm 66 in opposite directions adding to or subtracting from the speed of rotation of the planet carriers 102. Moreover, it will be observed that carried on the opposite sides of the front end of the machine frame are coaxial longitudinally spaced sets of guide sheaves 127 while supported by the opposite side of the rear end of the machine frame are guide sheaves 128, the guide sheaves 127, 128 cooperating to guide the cables 125, 126 during the various operations of the machine.

In the operation of my improved mining machine it will be noted that when the machine has been transported to the room of the mine on its transport truck and unloaded therefrom, one or the other of the cables 125, 126 may be extended to a point adjacent the right hand rib of the coal and its free end anchored by a suitable roof jack or take up device. The operator then manipulates the operating member 82 in a suitable manner, causing the clutch teeth 69 on the clutch member 67 to be connected to the clutch teeth 71 formed on the worm 66, rotating the latter at its fast speed in the opposite direction to the rotation of the worm 65 and consequently in view of the opposite threads of the worms the worm gears 83, 88 and 84, 89 are rotated in the same direction, causing the planet carriers 102 to rotate the shafts 93, 94 at a relatively high speed. The desired drum 123, 124 is then connected in operative driving relation with the driving shaft by means of the clutch 108, 109 and the desired feed cable wound in and the machine fed toward the right hand rib at a fast or moving speed. When the cutter bar reaches the desired position adjacent the face of the coal, the feed cable 125 is extended laterally from the drum 123 between certain of the sets of guide sheaves 127 and from the advancing side of the machine to the left hand rib of the coal, the free end of the cable being anchored in position by a suitable roof jack or take up device. The cable 126 is then fed rearwardly about the right hand sheave 128 and forwardly to a jack near the right hand rib. The operator then manipulates the operating member 82 and the cutter chain drive sprocket 21 is connected in operative driving relation with the shaft 17, consequently causing the cutter chain 22 to be rapidly circulated about the cutter bar. The operating member 82 is then manipulated to bring the clutch members 67 and 68 into their neutral position, rotation of the worm 66 being prevented at that time due to its self-locking feature. As the worm 65 is constantly driven the worm gears 88 and 89 and the bevel gears 91 and 92 are again rotated, thus causing the planetary pinions 99 and 100 to react on the stationary bevel gears 86 and 87, respectively, consequently causing the planet carriers 102 to drive the shafts 93, 94 at an intermediate speed suitable for sumping. The friction clutch controlling the drum 124 is then applied and the cable 126 drawn in and the cutter bar sumped into the face of the coal at an intermediate or sumping speed, the friction clutch controlling rotation of the drum 123 maintaining a desired controlling tension on the cable 125 at that time. On completion of sumping, the clutch teeth 70 on the clutch member 68 are thrown into engagement with the clutch teeth 73 formed on the worm 66, causing the latter to be rotated at a much slower speed and in the same direction as the rotation of the worm 65. The bevel gears 86 and 87 are then rotated in opposite directions from the rotation of the bevel gears 91 and 92, but more slowly, thus subtracting from the speed of rotation of the planet carriers 102, causing the shafts 92, 94 to be driven at a slow speed though still in the same direction. The friction clutch controlling the drum 123 is then connected, causing the latter to wind in the cable 125 and the machine is drawn up and fed laterally across the face at a slow or

cutting speed, the drum 124 acting on the receding cable 126 maintaining a desired controlling tension thereon, thus preventing the cutter bar from being swung out of the kerf. It will also herein be noted that by suitable operation of the clutches controlling the drums 123, 124 the angle of the machine relative to the face of the coal may be controlled at will. Other operations of my improved mining machine will be clearly apparent to those skilled in the art.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining machine, a motor, cutting mechanism driven thereby, and feeding means driven by the front end of said motor comprising a feed operating member, and means for transmitting power to said member including a plurality of coaxial members, two of which support coaxial gear members and another of which supports planet means meshing with said gear members, means for effecting rotation of two of said members by power from said motor, and means connecting the other of said members in driving relation to said feed operating member.

2. In a mining machine, a motor, cutting mechanism driven thereby, and feeding means driven by the front end of said motor comprising a feed operating member, and means for transmitting power to said member including a plurality of coaxial members, two of which support coaxial gear members and another of which supports planet means meshing with said gear members, means for effecting rotation of the first two of said members by power from said motor, and means connecting the other of said members in driving relation to said feed operating member.

3. In a mining machine, a motor, a cutting mechanism driven thereby, and feeding means driven by the front end of said motor comprising a feed operating member, and means for transmitting power to said member including a plurality of coaxial members rotating on horizontal axes, two of which support coaxial gear members and another of which supports planet means meshing with said gear members, means for effecting rotation of two of said members by power from said motor, and means connecting the other of said members in driving relation to said feed operating member.

4. In a mining machine, a motor, cutting mechanism driven thereby, and feeding means driven by the front end of said motor comprising a feed operating member, and means for transmitting power to said member including a plurality of coaxial members rotating on horizontal axes, two of which support coaxial gear members and another of which supports planet means meshing with said gear members, means for effecting rotation of the first two of said members by power from said motor, and means connecting the other of said members in driving relation to said feed operating member.

5. In a mining machine, a motor, cutting mechanism driven thereby, and feeding means driven by the front end of said motor comprising a feed operating member, and means for transmitting power to said member including a plurality of coaxial members rotating on horizontal axes extending longitudinally of the machine, two of which support coaxial gear members and another of which supports planet means meshing with said gear members, means for effecting rotation of two of said members by power from said motor, and means connecting the other of said members in driving relation to said feed operating member.

6. In a mining machine, a motor, cutting mechanism driven thereby, and feeding means driven by the front end of said motor comprising a feed operating member, and means for transmitting power to said member including a plurality of coaxial members rotating on horizontal axes extending longitudinally of the machine, two of which support coaxial gear members and another of which supports planet means meshing with said gear members, means for effecting rotation of the first two of said members by power from said motor, and means connecting the other of said members in driving relation to said feed operating member.

7. In a mining machine, a motor, cutting mechanism driven thereby, and feeding means driven by the front end of said motor comprising a plurality of feed operating members, and means for transmitting power to said members including a plurality of gearing units one individual to each of said members and each comprising a plurality of coaxial members, two of which support coaxial gear members and another of which supports planet means meshing with said gear members, means for effecting rotation of two of said members of each set by power from said motor, and means connecting the others of said members in driving relation to said feed operating members.

8. In a mining machine, a motor, cutting mechanism driven thereby, and feeding

- means driven by the front end of said motor comprising a plurality of feed operating members, and means for transmitting power to said members including a plurality of gearing units one individual to each of said members and each comprising a plurality of coaxial members, two of which support coaxial gear members and another of which supports planet means meshing with said gear members, means for effecting rotation of the first two of said members of each set by power from said motor, and means connecting the others of said members in driving relation to said feed operating members. 5
9. In a mining machine, a motor, cutting mechanism driven thereby, and feeding means driven by the front end of said motor comprising a plurality of feed operating members, and means for transmitting power to said members including a plurality of gearing units one individual to each of said members and each comprising a plurality of coaxial members rotating on horizontal axes, two of which support coaxial gear members and another of which supports planet means meshing with said gear members, means for effecting rotation of two of said members of each set by power from said motor, and means connecting the others of said members in driving relation to said feed operating members. 20
10. In a mining machine, a motor, cutting mechanism driven thereby, and feeding means driven by the front end of said motor comprising a plurality of feed operating members, and means for transmitting power to said members including a plurality of gearing units one individual to each of said members and each comprising a plurality of coaxial members rotating on horizontal axes, two of which support coaxial gear members and another of which supports planet means meshing with said gear members, means for effecting rotation of the first two of said members of each set by power from said motor, and means connecting the others of said members in driving relation to said feed operating members. 25
11. In a mining machine, a motor, cutting mechanism driven thereby, and feeding means driven by the front end of said motor comprising a plurality of feed operating members, and means for transmitting power to said members including a plurality of gearing units one individual to each of said members and each comprising a plurality of coaxial members rotating on horizontal axes, two of which support coaxial gear members and another of which supports planet means meshing with said gear members, means for effecting rotation of the first two of said members of each set by power from said motor, and means connecting the others of said members in driving relation to said feed operating members. 30
12. In a mining machine, a motor, cutting mechanism driven thereby, and feeding means driven by the front end of said motor comprising a plurality of feed operating members, and means for transmitting power to said members including a plurality of gearing units one individual to each of said members and each comprising a plurality of coaxial members rotating on horizontal axes, two of which support coaxial gear members and another of which supports planet means meshing with said gear members, means for effecting rotation of the first two of said members of each set by power from said motor, and means connecting the others of said members in driving relation to said feed operating members. 35
13. In a mining machine, a motor, cutting mechanism driven thereby, and feeding means driven by the front end of said motor comprising a feed operating member, and means for transmitting power to said member including a plurality of coaxial members, two of which support coaxial gear members and another of which supports planet means meshing with said gear members, means for effecting rotation of two of said members by power from said motor including worms driven from the front end of the motor, and means connecting the other of said members in driving relation to said feed operating member. 40
14. In a mining machine, a motor, cutting mechanism driven thereby, and feeding means driven by the front end of said motor comprising a feed operating member, and means for transmitting power to said member including a plurality of coaxial members, two of which support coaxial gear members and another of which supports planet means meshing with said gear members, means for effecting rotation of the first two of said members by power from said motor including worms driven from the front end of the motor, and means connecting the other of said members in driving relation to said feed operating member. 45
15. In a mining machine, a motor, cutting mechanism driven thereby, and feeding means driven by the front end of said motor comprising a feed operating member, and means for transmitting power to said member including a plurality of coaxial members rotating on horizontal axes, two of which support coaxial gear members and another of which supports planet means meshing with said gear members, means for effecting rotation of two of said members by power from said motor including worms driven from the front end of the motor, and

- means connecting the other of said members in driving relation to said feed operating member.
16. In a mining machine, a motor, cutting mechanism driven thereby, and feeding means driven by the front end of said motor comprising a feed operating member, and means for transmitting power to said member including a plurality of coaxial members 10 rotating on horizontal axes, two of which support coaxial gear members and another of which supports planet means meshing with said gear members, means for effecting rotation of the first two of said members by 15 power from said motor including worms driven from the front end of the motor, and means connecting the other of said members in driving relation to said feed operating member.
17. In a mining machine, a motor, cutting mechanism driven thereby, and feeding means driven by the front end of said motor comprising a feed operating member, and means for transmitting power to said member including a plurality of coaxial members 20 rotating on horizontal axes extending longitudinally of the machine, two of which support coaxial gear members and another of which supports planet means meshing 25 with said gear members, means for effecting rotation of two of said members by power from said motor including worms driven from the front end of the motor, and means connecting the other of said members in 30 driving relation to said feed operating member.
18. In a mining machine, a motor, cutting mechanism driven thereby, and feeding means driven by the front end of said motor comprising a feed operating member, and means for transmitting power to said member including a plurality of coaxial members 35 rotating on horizontal axes extending longitudinally of the machine, two of which support coaxial gear members and another of which supports planet means meshing with said gear members, means for effecting rotation of the first two of said members by power from said motor including worms driven from the front end of the motor, and means connecting the other of said members in 40 driving relation to said feed operating member.
19. In a mining machine, a motor, cutting mechanism driven thereby, and feeding means driven by the front end of said motor comprising a plurality of feed operating members, and means for transmitting power to said members including a plurality of 45 gearing units one individual to each of said members and each comprising a plurality of coaxial members, two of which support coaxial gear members and another of which supports planet means meshing with said gear members, means for effecting rotation of the first two of said members by power from said motor including worms driven from the front end of the motor, and means connecting the other of said members in 50 driving relation to said feed operating member.
20. In a mining machine, a motor, cutting mechanism driven thereby, and feeding means driven by the front end of said motor comprising a plurality of feed operating members, and means for transmitting power to said members including a plurality of gearing units one individual to each of said members and each comprising a plurality of coaxial members, two of which support coaxial gear members and another of which supports planet means meshing with said gear members, means for effecting rotation of the first two of said members by power from said motor including worms driven from the front end of the motor, and means connecting the other of said members in 55 driving relation to said feed operating members.
21. In a mining machine, a motor, cutting mechanism driven thereby, and feeding means driven by the front end of said motor comprising a plurality of feed operating members, and means for transmitting power to said members including a plurality of gearing units one individual to each of said members and each comprising a plurality of coaxial members rotating on horizontal axes, two of which support coaxial gear members and another of which supports planet means meshing with said gear members, means for effecting rotation of two of said members of each set by power from said motor including worms driven from the front end of the motor, and means connecting the other of said members in 60 driving relation to said feed operating members.
22. In a mining machine, a motor, cutting mechanism driven thereby, and feeding means driven by the front end of said motor comprising a plurality of feed operating members, and means for transmitting power to said members including a plurality of gearing units one individual to each of said members and each comprising a plurality of coaxial members rotating on horizontal axes, two of which support coaxial gear members and another of which supports planet means meshing with said gear members, means for effecting rotation of the first two of said members of each set by power from said motor including worms driven from the front end of the motor, and means connecting the other of said members in 65 driving relation to said feed operating members.
23. In a mining machine, a motor, cutting mechanism driven thereby, and feeding means driven by the front end of said motor comprising a plurality of feed operating members, and means for transmitting power 70

- to said members including a plurality of gearing units one individual to each of said members and each comprising a plurality of coaxial members rotating on horizontal axes 5 extending longitudinally of the machine, two of which support coaxial gear members and another of which supports planet means meshing with said gear members, means for effecting rotation of two of said members 10 of each set by power from said motor including worms driven from the front end of the motor, and means connecting the others of said members in driving relation to said feed operating members.

15 24. In a mining machine, a motor, cutting mechanism driven thereby, and feeding means driven by the front end of said motor comprising a plurality of feed operating members, and means for transmitting power 20 to said members including a plurality of gearing units one individual to each of said members and each comprising a plurality of coaxial members rotating on horizontal axes 25 extending longitudinally of the machine, two of which support coaxial gear members and another of which supports planet means meshing with said gear members, means for effecting rotation of the first two of said members of each set by power from said 30 motor including worms driven from the front end of the motor, and means connecting the others of said members in driving relation to said feed operating members.

35 25. In a mining machine, a motor, cutting mechanism driven thereby, and feeding means driven by the front end of said motor comprising a feed operating member, and means for transmitting power to said member including a plurality of coaxial members, two of which support coaxial gear 40 members and another of which supports planet means meshing with said gear members, means for effecting rotation of two of said members by power from said motor including worms rotating on parallel axes and 45 driven from the front end of the motor, and means connecting the other of said members in driving relation to said feed operating member.

50 26. In a mining machine, a motor, cutting mechanism driven thereby, and feeding means driven by the front end of said motor comprising a feed operating member, and means for transmitting power to said member including a plurality of coaxial members, two of which support coaxial gear members and another of which supports planet means 55 meshing with said gear members, means for effecting rotation of the first two of said members by power from said motor including worms rotating on parallel axes and 60 driven from the front end of the motor, and means connecting the other of said members in driving relation to said feed operating member.

65 27. In a mining machine, a motor, cutting mechanism driven thereby, and feeding means driven by the front end of said motor comprising a feed operating member, and means for transmitting power to said member including a plurality of coaxial members 70 rotating on horizontal axes, two of which support coaxial gear members and another of which supports planet means meshing with said gear members, means for effecting 75 rotation of two of said members by power from said motor including worms rotating on parallel axes and driven from the front end of the motor, and means connecting the other of said members in driving relation to 80 said feed operating member.

85 28. In a mining machine, a motor, cutting mechanism driven thereby, and feeding means driven by the front end of said motor comprising a feed operating member, and means for transmitting power to said member including a plurality of coaxial members 90 rotating on horizontal axes, two of which support coaxial gear members and another of which supports planet means meshing with said gear members, means for effecting 95 rotation of the first two of said members by power from said motor including worms rotating on parallel axes and driven from the front end of the motor, and means connecting the other of said members in driving relation to 100 said feed operating member.

105 29. In a mining machine, a motor, cutting mechanism driven thereby, and feeding means driven by the front end of said motor comprising a feed operating member, and means for transmitting power to said member including a plurality of coaxial members 110 rotating on horizontal axes extending longitudinally of the machine, two of which support coaxial gear members and another of which supports planet means meshing with said gear members, means for effecting 115 rotation of two of said members by power from said motor including worms rotating on parallel axes and driven from the front end of the motor, and means connecting the other of said members in driving relation to 120 said feed operating member.

125 30. In a mining machine, a motor, cutting mechanism driven thereby, and feeding means driven by the front end of said motor comprising a feed operating member, and means for transmitting power to said member including a plurality of coaxial members 125 rotating on horizontal axes extending longitudinally of the machine, two of which support coaxial gear members and another of which supports planet means meshing with said gear members, means for effecting rotation of the first two of said members by power from said motor including worms rotating on parallel axes and driven 130 from the front end of the motor, and means

connecting the other of said members in driving relation to said feed operating member.

31. In a mining machine, a motor, cutting mechanism driven thereby, and feeding means driven by the front end of said motor comprising a plurality of feed operating members, and means for transmitting power to said members including a plurality of gearing units one individual to each of said members and each comprising a plurality of coaxial members, two of which support coaxial gear members and another of which supports planet means meshing with said gear members, means for effecting rotation of the first two of said members of each set by power from said motor including worms rotating on parallel axes and driven from the front end of the motor, and means connecting the others of said members in driving relation to said feed operating members.

32. In a mining machine, a motor, cutting mechanism driven thereby, and feeding means driven by the front end of said motor comprising a plurality of feed operating members, and means for transmitting power to said members including a plurality of gearing units one individual to each of said members and each comprising a plurality of coaxial members, two of which support coaxial gear members and another of which supports planet means meshing with said gear members, means for effecting rotation of the first two of said members of each set by power from said motor including worms rotating on parallel axes and driven from the front end of the motor, and means connecting the others of said members in driving relation to said feed operating members.

33. In a mining machine, a motor, cutting mechanism driven thereby, and feeding means driven by the front end of said motor comprising a plurality of feed operating members, and means for transmitting power to said members including a plurality of gearing units one individual to each of said members and each comprising a plurality of coaxial members rotating on horizontal axes, two of which support coaxial gear members and another of which supports planet means meshing with said gear members, means for effecting rotation of two of said members of each set by power from said motor including worms rotating on parallel axes and driven from the front end of the motor, and means connecting the others of said members in driving relation to said feed operating members.

34. In a mining machine, a motor, cutting mechanism driven thereby, and feeding means driven by the front end of said motor comprising a plurality of feed operating members, and means for transmitting power to said members including a plurality of

gearing units one individual to each of said members and each comprising a plurality of coaxial members rotating on horizontal axes, two of which support coaxial gear members and another of which supports planet means meshing with said gear members, means for effecting rotation of the first two of said members of each set by power from said motor including worms rotating on parallel axes and driven from the front end of the motor, and means connecting the others of said members in driving relation to said feed operating members.

35. In a mining machine, a motor, cutting mechanism driven thereby, and feeding means driven by the front end of said motor comprising a plurality of feed operating members, and means for transmitting power to said members including a plurality of gearing units one individual to each of said members and each comprising a plurality of coaxial members rotating on horizontal axes extending longitudinally of the machine, two of which support coaxial gear members and another of which supports planet means meshing with said gear members, means for effecting rotation of two of said members of each set by power from said motor including worms rotating on parallel axes and driven from the front end of the motor, and means connecting the others of said members in driving relation to said feed operating members.

36. In a mining machine, a motor, cutting mechanism driven thereby, and feeding means driven by the front end of said motor comprising a plurality of feed operating members, and means for transmitting power to said members including a plurality of gearing units one individual to each of said members and each comprising a plurality of coaxial members rotating on horizontal axes extending longitudinally of the machine, two of which support coaxial gear members and another of which supports planet means meshing with said gear members, means for effecting rotation of the first two of said members of each set by power from said motor including worms rotating on parallel axes and driven from the front end of the motor, and means connecting the others of said members in driving relation to said feed operating members.

37. In a mining machine, a motor, cutting mechanism driven thereby, and feeding means driven by the front end of said motor comprising a feed operating member, and means for transmitting power to said member including a plurality of coaxial members, two of which support coaxial gear members and another of which supports planet means meshing with said gear members, means for effecting rotation of two of said members by power from said motor including worms rotating on vertical axes and

driven from the front end of the motor, and means connecting the other of said members in driving relation to said feed operating member.

by power from said motor including worms rotating on vertical axes and driven from the front end of the motor, and means connecting the other of said members in driving relation to said feed operating member.

5 38. In a mining machine, a motor, cutting mechanism driven thereby, and feeding means driven by the front end of said motor comprising a feed operating member, and means for transmitting power to said member including a plurality of coaxial members, two of which support coaxial gear members and another of which supports planet means meshing with said gear members, means for effecting rotation of the first
10 two of said members by power from said motor including worms rotating on vertical axes and driven from the front end of the motor, and means connecting the other of said members in driving relation to said
15 feed operating member.
20

relation to said feed operating member.

39. In a mining machine, a motor, cutting mechanism driven thereby, and feeding means driven by the front end of said motor comprising a feed operating member, and
25 means for transmitting power to said member including a plurality of coaxial members rotating on horizontal axes, two of which support coaxial gear members and another of which supports planet means meshing
30 with said gear members, means for effecting rotation of two of said members by power from said motor including worms rotating on vertical axes and driven from the front end of the motor, and means connecting the other of said members in driving relation to said feed operating member.

ing the other of said members in driving relation to said feed operating member.

40. In a mining machine, a motor, cutting mechanism driven thereby, and feeding means driven by the front end of said motor comprising a feed operating member, and means for transmitting power to said member including a plurality of coaxial members rotating on horizontal axes, two of which support coaxial gear members and another of which supports planet means meshing with said gear members, means for effecting rotation of the first two of said members by power from said motor including worms rotating on vertical axes and driven from the front end of the motor, and means connecting the other of said members in driving relation to said feed operating member.

rotating on vertical axes and driven from the front end of the motor, and means connecting the others of said members in driving relation to said feed operating members.

41. In a mining machine, a motor, cutting mechanism driven thereby, and feeding means driven by the front end of said motor comprising a feed operating member, and means for transmitting power to said member including a plurality of coaxial members 55 rotating on horizontal axes extending longitudinally of the machine, two of which support coaxial gear members and another of which supports planet means meshing with said gear members, means for 60 effecting rotation of two of said members 65

set by power from said motor including worms rotating on vertical axes and driven from the front end of the motor, and means connecting the others of said members in driving relation to said feed operating members.

45. In a mining machine, a motor, cutting mechanism driven thereby, and feeding means driven by the front end of said motor comprising a plurality of feed operating members, and means for transmitting power to said members including a plurality of

gearing units one individual to each of said members and each comprising a plurality of coaxial members rotating on horizontal axes, two of which support coaxial gear members and another of which supports planet means meshing with said gear members, means for effecting rotation of two of said members of each set by power from said motor including worms rotating on vertical axes and driven from the front end of the motor, and means connecting the others of said members in driving relation to said feed operating members.

10 46. In a mining machine, a motor, cutting

15 mechanism driven thereby, and feeding means driven by the front end of said motor comprising a plurality of feed operating members, and means for transmitting power to said members including a plurality of 20 gearing units one individual to each of said members and each comprising a plurality of coaxial members rotating on horizontal axes, two of which support coaxial gear members and another of which supports 25 planet means meshing with said gear members, means for effecting rotation of the first two of said members of each set by power from said motor including worms rotating on vertical axes and driven from the front 30 end of the motor, and means connecting the others of said members in driving relation to said feed operating members.

47. In a mining machine, a motor, cutting mechanism driven thereby, and feeding

35 means driven by the front end of said motor comprising a plurality of feed operating members, and means for transmitting power to said members including a plurality of 40 gearing units one individual to each of said members and each comprising a plurality of coaxial members rotating on horizontal axes extending longitudinally of the machine, two of which support coaxial gear members and another of which supports planet means 45 meshing with said gear members, means for effecting rotation of two of said members of each set by power from said motor including worms rotating on vertical axes and driven from the front end of the motor, and 50 means connecting the others of said members in driving relation to said feed operating members.

48. In a mining machine, a motor, cutting mechanism driven thereby, and feeding

55 means driven by the front end of said motor comprising a plurality of feed operating members, and means for transmitting power to said members including a plurality of 60 gearing units one individual to each of said members and each comprising a plurality of coaxial members rotating on horizontal axes extending longitudinally of the machine, two of which support coaxial gear members and another of which supports planet means 65 meshing with said gear members, means for

effecting rotation of the first two of said members of each set by power from said motor including worms rotating on vertical axes and driven from the front end of the motor, and means connecting the others of 70 said members in driving relation to said feed operating members.

49. In a mining machine, a motor, cutting

75 mechanism driven thereby, and feeding means driven by the front end of said motor comprising a plurality of feed operating members, and means for transmitting power to said members including a plurality of gearing units one individual to each of said members and each comprising a plurality of coaxial members, two of which support coaxial gear members and another of which supports planet means meshing with said gear members, means for effecting 80 rotation of two of said members of each set by power from said motor including worms constituting driving elements common to each set and rotating on vertical axes, and means connecting the others of said members in driving relation to said feed operating members.

50. In a mining machine, a motor, cutting

85 mechanism driven thereby, and feeding means driven by the front end of said motor comprising a plurality of feed operating members, and means for transmitting power to said members including a plurality of 90 gearing units one individual to each of said members and each comprising a plurality of coaxial members, two of which support coaxial gear members and another of which supports planet means meshing with said gear members, means for effecting rotation of the first two of said members of each set by power from said motor including worms constituting driving elements common to each set and rotating on vertical axes, and means connecting the others of said members in driving relation to said feed operating members.

95 51. In a mining machine, a motor, cutting

100 mechanism driven thereby, and feeding means driven by the front end of said motor comprising a plurality of feed operating members, and means for transmitting power to said members including a plurality of 105 gearing units one individual to each of said members and each comprising a plurality of coaxial members rotating on horizontal axes, two of which support coaxial gear members and another of which supports planet means meshing with said gear members, means for effecting rotation of two of said members of each set by power from 110 said motor including worms constituting driving elements common to each set and rotating on vertical axes, and means connecting the others of said members in driving relation to said feed operating members.

115 52. In a mining machine, a motor, cutting

120

- mechanism driven thereby, and feeding means driven by the front end of said motor comprising a plurality of feed operating members, and means for transmitting power to said members including a plurality of gearing units one individual to each of said members and each comprising a plurality of coaxial members rotating on horizontal axes, two of which support coaxial gear members and another of which supports planet means meshing with said gear members, means for effecting rotation of the first two of said members of each set by power from said motor including worms constituting driving elements common to each set and rotating on vertical axes, and means connecting the others of said members in driving relation to said feed operating members.

53. In a mining machine, a motor, cutting mechanism driven thereby, and feeding means driven by the front end of said motor comprising a plurality of feed operating members, and means for transmitting power to said members including a plurality of gearing units one individual to each of said members and each comprising a plurality of coaxial members rotating on horizontal axes extending longitudinally of the machine, two of which support coaxial gear members and another of which supports planet means meshing with said gear members, means for effecting rotation of two of said members of each set by power from said motor including worms constituting driving elements common to each set and rotating on vertical axes, and means connecting the others of said members in driving relation to said feed operating members.

54. In a mining machine, a motor, cutting mechanism driven thereby, and feeding means driven by the front end of said motor comprising a plurality of feed operating members, and means for transmitting power to said members including a plurality of gearing units one individual to each of said members and each comprising a plurality of coaxial members rotating on horizontal axes extending longitudinally of the machine, two of which support coaxial gear members and another of which supports planet means meshing with said gear members, means for effecting rotation of the first two of said members of each set by power from said motor including worms constituting driving elements common to each set and rotating on vertical axes, and means connecting the others of said members in driving relation to said feed operating members.

55. In a mining machine, a motor, cutting mechanism driven thereby, and feeding means driven by the front end of said motor comprising a feed operating member, and means for transmitting power to said mem-

ber including in coaxial relation therewith a plurality of coaxial members, two of which support coaxial gear members and another of which supports planet means meshing with said gear members, means for effecting rotation of two of said members by power from said motor, and means connecting the other of said members in driving relation to said feed operating member.

56. In a mining machine, a motor, cutting mechanism driven thereby, and feeding means driven by the front end of said motor comprising a feed operating member, and means for transmitting power to said member including in coaxial relation therewith a plurality of coaxial members, two of which support coaxial gear members and another of which supports planet means meshing with said gear members, means for effecting rotation of the first two of said members by power from said motor, and means connecting the other of said members in driving relation to said feed operating member.

57. In a mining machine, a motor, cutting mechanism driven thereby, and feeding means driven by the front end of said motor comprising a feed operating member, and means for transmitting power to said member including in coaxial relation therewith a plurality of coaxial members rotating on horizontal axes, two of which support coaxial gear members and another of which supports planet means meshing with said gear members, means for effecting rotation of two of said members by power from said motor, and means connecting the other of said members in driving relation to said feed operating member.

58. In a mining machine, a motor, cutting mechanism driven thereby, and feeding means driven by the front end of said motor comprising a feed operating member, and means for transmitting power to said member including in coaxial relation therewith a plurality of coaxial members rotating on horizontal axes, two of which support coaxial gear members and another of which supports planet means meshing with said gear members, means for effecting rotation of the first two of said members by power from said motor, and means connecting the other of said members in driving relation to said feed operating member.

59. In a mining machine, a motor, cutting mechanism driven thereby, and feeding means driven by the front end of said motor comprising a feed operating member, and means for transmitting power to said member including in coaxial relation therewith a plurality of coaxial members rotating on horizontal axes extending longitudinally of the machine, two of which support coaxial gear members and another of which supports planet means meshing with said gear members, means for effecting rotation of the first two of said members by power from said motor, and means connecting the other of said members in driving relation to said feed operating member.

60. In a mining machine, a motor, cutting mechanism driven thereby, and feeding means driven by the front end of said motor comprising a feed operating member, and means for transmitting power to said mem-

members, means for effecting rotation of two of said members by power from said motor, and means connecting the other of said members in driving relation to said feed operating member.

60. In a mining machine, a motor, cutting mechanism driven thereby, and feeding means driven by the front end of said motor comprising a feed operating member, and means for transmitting power to said member including in coaxial relation therewith a plurality of coaxial members rotating on horizontal axes extending longitudinally of the machine, two of which support coaxial gear members and another of which supports planet means meshing with said gear members, means for effecting rotation of the first two of said members by power from said motor, and means connecting the other of said members in driving relation to said feed operating member.

61. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members, two of which support coaxial gear members and another of which supports planet means meshing with said gear members, means for effecting rotation of two of said members of each set by power from said motor, and means connecting the others of said members in driving relation to said feed operating members.

62. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members, two of which support coaxial gear members and another of which supports planet means meshing with said gear members, means for effecting rotation of the first two of said members of each set by power from said motor, and means connecting the others of said members in driving relation to said feed operating members.

63. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes, two of which

support coaxial gear members and another of which supports planet means meshing with said gear members, means for effecting rotation of two of said members of each set by power from said motor, and means connecting the others of said members in driving relation to said feed operating members.

64. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes, two of which support coaxial gear members and another of which supports planet means meshing with said gear members, means for effecting rotation of the first two of said members of each set by power from said motor, and means connecting the others of said members in driving relation to said feed operating members.

65. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes extending longitudinally of the machine, two of which support coaxial gear members and another of which supports planet means meshing with said gear members, means for effecting rotation of two of said members of each set by power from said motor, and means connecting the others of said members in driving relation to said feed operating members.

66. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes extending longitudinally of the machine, two of which support coaxial gear members and another of which supports planet means meshing with said gear members, means for effecting rotation of the first two of said members of each set by power from said motor, and means connecting the others of said members in driving relation to said feed operating members.

67. In a mining machine, a motor, cutting mechanism driven thereby, and feeding

- means driven by the front end of said motor comprising a feed operating member, and means for transmitting power to said member including in coaxial relation therewith a plurality of coaxial members, two of which support coaxial gear members and another of which supports planet means meshing with said gear members, means for effecting rotation of two of said members by power from said motor including worms driven from the front end of the motor, and means connecting the other of said members in driving relation to said feed operating member.
68. In a mining machine, a motor, cutting mechanism driven thereby, and feeding means driven by the front end of said motor comprising a feed operating member, and means for transmitting power to said member including in coaxial relation therewith a plurality of coaxial members, two of which support coaxial gear members and another of which supports planet means meshing with said gear members, means for effecting rotation of the first two of said members by power from said motor including worms driven from the front end of the motor, and means connecting the other of said members in driving relation to said feed operating member.
69. In a mining machine, a motor, cutting mechanism driven thereby, and feeding means driven by the front end of said motor comprising a feed operating member, and means for transmitting power to said member including coaxial therewith a plurality of coaxial members rotating on horizontal axes, two of which support coaxial gear members and another of which supports planet means meshing with said gear members, means for effecting rotation of two of said members by power from said motor including worms driven from the front end of the motor, and means connecting the other of said members in driving relation to said feed operating member.
70. In a mining machine, a motor, cutting mechanism driven thereby, and feeding means driven by the front end of said motor comprising a feed operating member, and means for transmitting power to said member including coaxial therewith a plurality of coaxial members rotating on horizontal axes, two of which support coaxial gear members and another of which supports planet means meshing with said gear members, means for effecting rotation of the first two of said members by power from said motor including worms driven from the front end of the motor, and means connecting the other of said members in driving relation to said feed operating member.
71. In a mining machine, a motor, cutting mechanism driven thereby, and feeding means driven by the front end of said motor comprising a feed operating member, and means for transmitting power to said member including coaxial therewith a plurality of coaxial members rotating on horizontal axes, two of which support coaxial gear members and another of which supports planet means meshing with said gear members, means for effecting rotation of the first two of said members by power from said motor including worms driven from the front end of the motor, and means connecting the other of said members in driving relation to said feed operating member.
72. In a mining machine, a motor, cutting mechanism driven thereby, and feeding means driven by the front end of said motor comprising a feed operating member, and means for transmitting power to said member including coaxial therewith a plurality of coaxial members rotating on horizontal axes extending longitudinally of the machine, two of which support coaxial gear members and another of which supports planet means meshing with said gear members, means for effecting rotation of two of said members by power from said motor including worms driven from the front end of the motor, and means connecting the other of said members in driving relation to said feed operating member.
73. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members, two of which support coaxial gear members and another of which supports planet means meshing with said gear members, means for effecting rotation of two of said members of each set by power from said motor including worms driven from the front end of the motor, and means connecting the other of said members in driving relation to said feed operating member.
74. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members, two of which support coaxial gear members and another of which supports planet means meshing with said gear members, means for effecting rotation of the first two of said members of each set by power from said motor including worms driven from the front end of the motor, and means connecting the other of said members in driving relation to said feed operating member.

ing the others of said members in driving relation to said feed operating members.

75. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes, two of which support coaxial gear members and another of which supports planet means meshing with said gear members, means for effecting rotation of two of said members of each set by power from said motor including worms driven from the front end of the motor, and means connecting the others of said members in driving relation to said feed operating members.

76. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes, two of which support coaxial gear members and another of which supports planet means meshing with said gear members, means for effecting rotation of the first two of said members of each set by power from said motor including worms driven from the front end of the motor, and means connecting the others of said members in driving relation to said feed operating members.

77. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes extending longitudinally of the machine, two of which support coaxial gear members and another of which supports planet means meshing with said gear members, means for effecting rotation of two of said members of each set by power from said motor including worms driven from the front end of the motor, and means connecting the others of said members in driving relation to said feed operating members.

78. In a mining machine, a motor, cutting mechanism driven thereby, and feeding means driven by the front end of said motor comprising a plurality of feed operating members, and means for transmitting power

to said members including a plurality of gearing units one individual to and coaxial with each of said members and each comprising a plurality of coaxial members rotating on horizontal axes extending longitudinally of the machine, two of which support coaxial gear members and another of which supports planet means meshing with said gear members, means for effecting rotation of the first two of said members of each set by power from said motor including worms driven from the front end of the motor, and means connecting the others of said members in driving relation to said feed operating members.

79. In a mining machine, a motor, cutting mechanism driven thereby, and feeding means driven by the front end of said motor comprising a feed operating member, and means for transmitting power to said member including coaxial therewith a plurality of coaxial members, two of which support coaxial gear members and another of which supports planet means meshing with said gear member, means for effecting rotation of two of said members by power from said motor including worms rotating on parallel axes and driven from the front end of the motor, and means connecting the other of members in driving relation to said feed operating member.

80. In a mining machine, a motor, cutting mechanism driven thereby, and feeding means driven by the front end of said motor comprising a feed operating member, and means for transmitting power to said member including coaxial therewith a plurality of coaxial members, two of which support coaxial gear members and another of which supports planet means meshing with said gear members, means for effecting rotation of the first two of said members by power from said motor including worms rotating on parallel axes and driven from the front end of the motor, and means connecting the other of said members in driving relation to said feed operating member.

81. In a mining machine, a motor, cutting mechanism driven thereby, and feeding means driven by the front end of said motor comprising a feed operating member, and means for transmitting power to said member including coaxial therewith a plurality of coaxial members rotating on horizontal axes, two of which support coaxial gear members and another of which supports planet means meshing with said gear members, means for effecting rotation of two of said members by power from said motor including worms rotating on parallel axes and driven from the front end of the motor, and means connecting the other of said members in driving relation to said feed operating member.

82. In a mining machine, a motor, cutting

mechanism driven thereby, and feeding means driven by the front end of said motor comprising a feed operating member, and means for transmitting power to said member including coaxial therewith a plurality of coaxial members rotating on horizontal axes, two of which support coaxial gear members and another of which supports planet means meshing with said gear members, means for effecting rotation of the first two of said members by power from said motor including worms rotating on parallel axes and driven from the front end of the motor, and means connecting the other of said members in driving relation to said feed operating member.

83. In a mining machine, a motor, cutting mechanism driven thereby, and feeding means driven by the front end of said motor comprising a feed operating member, and means for transmitting power to said member including coaxial therewith a plurality of coaxial members rotating on horizontal axes extending longitudinally of the machine, two of which support coaxial gear members and another of which supports planet means meshing with said gear members, means for effecting rotation of two of said members by power from said motor including worms rotating on parallel axes and driven from the front end of the motor, and means connecting the other of said members in driving relation to said feed operating member.

35 84. In a mining machine, a motor, cutting mechanism driven thereby, and feeding means driven by the front end of said motor comprising a feed operating member, and means for transmitting power to said member including coaxial therewith a plurality of coaxial members rotating on horizontal axes extending longitudinally of the machine, two of which support coaxial gear members and another of which supports 40 planet means meshing with said gear members, means for effecting rotation of the first two of said members by power from said motor including worms rotating on parallel axes and driven from the front end of the 45 motor, and means connecting the other of said members in driving relation to said feed operating member.

85. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members, two of which support coaxial gear members and another of which supports planet means meshing with said gear members, means for effecting rotation of two of said members of

each set by power from said motor including worms rotating on parallel axes and driven from the front end of the motor, and means connecting the others of said members in driving relation to said feed operating members. 70

86. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members, two of which support coaxial gear members and another of which supports planet means meshing with said gear members, means for effecting rotation of the first two of said members of each set by power from said motor including worms rotating on parallel axes and driven from the front end of the motor, and means connecting the others of said members in driving relation to said feed operating members. 75 80 85 90

87. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes, two of which support coaxial gear members and another of which supports planet means meshing with said gear members, means for effecting rotation of two of said members of each set by power from said motor including worms rotating on parallel axes and driven from the front end of the motor, and means connecting the others of said members in driving relation to said feed operating members.

88. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes, two of which support coaxial gear members and another of which supports planet means meshing with said gear members, means for effecting rotation of the first two of said members of each set by power from said motor including worms rotating on parallel axes and driven from the front end of the motor, and means connecting the others of said members in driving relation to said feed operating members.

89. In a mining machine, a motor, cutting 130

- mechanism driven thereby, and feeding means driven by the front end of said motor comprising a plurality of feed operating members, and means for transmitting power 5 to said members including a plurality of gearing units one individual to and coaxial with each of said members and each comprising a plurality of coaxial members rotating on horizontal axes extending longitudinally 10 of the machine, two of which support coaxial gear members and another of which supports planet means meshing with said gear members, means for effecting rotation of two of said members of each set by power 15 from said motor including worms rotating on parallel axes and driven from the front end of the motor, and means connecting the others of said members in driving relation to said feed operating members.
- 20 90. In a mining machine, a motor, cutting mechanism driven thereby, and feeding means driven by the front end of said motor comprising a plurality of feed operating members, and means for transmitting power 25 to said members including a plurality of gearing units one individual to and coaxial with each of said members and each comprising a plurality of coaxial members rotating on horizontal axes extending longitudinally 30 of the machine, two of which support coaxial gear members and another of which supports planet means meshing with said gear members, means for effecting rotation of the first two of said members of 35 each set by power from said motor including worms rotating on parallel axes and driven from the front end of the motor, and means connecting the others of said members in driving relation to said feed operating members.
- 40 91. In a mining machine, a motor, cutting mechanism driven thereby, and feeding means driven by the front end of said motor comprising a feed operating member, and 45 means for transmitting power to said member including coaxial therewith a plurality of coaxial members, two of which support coaxial gear members and another of which supports planet means meshing with said 50 gear members, means for effecting rotation of two of said members by power from said motor including worms rotating on vertical axes and driven from the front end of the motor, and means connecting the other of 55 said members in driving relation to said feed operating member.
92. In a mining machine, a motor, cutting mechanism driven thereby, and feeding means driven by the front end of said motor 60 comprising a feed operating member, and means for transmitting power to said member including coaxial therewith a plurality of coaxial members, two of which support coaxial gear members and another of which 65 supports planet means meshing with said

gear members, means for effecting rotation of the first two of said members by power from said motor including worms rotating on vertical axes and driven from the front end of the motor, and means connecting the other of said members in driving relation to said feed operating member.

93. In a mining machine, a motor, cutting mechanism driven thereby, and feeding means driven by the front end of said motor comprising a feed operating member, and means for transmitting power to said member including coaxial therewith a plurality of coaxial members rotating on horizontal axes, two of which support coaxial gear members and another of which supports planet means meshing with said gear members, means for effecting rotation of two of said members by power from said motor including worms rotating on vertical axes and driven from the front end of the motor, and means connecting the other of said members in driving relation to said feed operating member.

94. In a mining machine, a motor, cutting mechanism driven thereby, and feeding means driven by the front end of said motor comprising a feed operating member, and means for transmitting power to said member including coaxial therewith a plurality of coaxial members rotating on horizontal axes, two of which support coaxial gear members and another of which supports planet means meshing with said gear members, means for effecting rotation of the first two of said members by power from said motor including worms rotating on vertical axes and driven from the front end of the motor, and means connecting the other of said members in driving relation to said feed operating member.

95. In a mining machine, a motor, cutting mechanism driven thereby, and feeding means driven by the front end of said motor comprising a feed operating member, and means for transmitting power to said member including coaxial therewith a plurality of coaxial members rotating on horizontal axes extending longitudinally of the machine, two of which support coaxial gear members and another of which supports planet means meshing with said gear members, means for effecting rotation of two of said members by power from said motor including worms rotating on vertical axes and driven from the front end of the motor, and means connecting the other of said members in driving relation to said feed operating member.

96. In a mining machine, a motor, cutting mechanism driven thereby, and feeding means driven by the front end of said motor comprising a feed operating member, and means for transmitting power to said member including coaxial therewith a plurality

- of coaxial members rotating on horizontal axes extending longitudinally of the machine, two of which support coaxial gear members and another of which supports a planet means meshing with said gear members, means for effecting rotation of the first two of said members by power from said motor including worms rotating on vertical axes and driven from the front end of the motor, and means connecting the other of said members in driving relation to said feed operating member.
97. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members, two of which support coaxial gear members and another of which supports planet means meshing with said gear members, means for effecting rotation of two of said members of each set by power from said motor including worms rotating on vertical axes and driven from the front end of the motor, and means connecting the others of said members in driving relation to said feed operating members.
98. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members, two of which support coaxial gear members and another of which supports planet means meshing with said gear members, means for effecting rotation of the first two of said members of each set by power from said motor including worms rotating on vertical axes and driven from the front end of the motor, and means connecting the others of said members in driving relation to said feed operating members.
99. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes, two of which support coaxial gear members and another of which supports planet means meshing with said gear members, means for effecting rotation of two of said members of each set by power from said motor including worms rotating on vertical axes and driven from the front end of the motor, and means connecting the others of said members in driving relation to said feed operating members.
100. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes, two of which support coaxial gear members and another of which supports planet means meshing with said gear members, means for effecting rotation of the first two of said members of each set by power from said motor including worms rotating on vertical axes and driven from the front end of the motor, and means connecting the others of said members in driving relation to said feed operating members.
101. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes extending longitudinally of the machine, two of which support coaxial gear members and another of which supports planet means meshing with said gear members, means for effecting rotation of two of said members of each set by power from said motor including worms rotating on vertical axes and driven from the front end of the motor, and means connecting the others of said members in driving relation to said feed operating members.
102. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes extending longitudinally of the machine, two of which support coaxial gear members and another of which supports planet means meshing with said gear members, means for effecting rotation of the first two of said members of each set by power from said motor including worms rotating on vertical axes and driven from the front end of the motor, and means connecting the others of said members in driving relation to said feed operating members.
103. In a mining machine, a motor, cut-

ting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members, two of which support coaxial gear members and another of which supports planet means meshing with said gear members, means for effecting rotation of two of said members of each set by power from said motor including worms constituting driving elements common to each set and rotating on vertical axes, and means connecting the others of said members in driving relation to said feed operating members.

104. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members, two of which support coaxial gear members and another of which supports planet means meshing with said gear members, means for effecting rotation of the first two of said members of each set by power from said motor including worms constituting driving elements common to each set and rotating on vertical axes, and means connecting the others of said members in driving relation to said feed operating members.

105. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes, two of which support coaxial gear members and another of which supports planet means meshing with said gear members, means for effecting rotation of two of said members of each set by power from said motor including worms constituting driving elements common to each set and rotating on vertical axes, and means connecting the others of said members in driving relation to said feed operating members.

106. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising

ing a plurality of coaxial members rotating on horizontal axes, two of which support coaxial gear members and another of which supports planet means meshing with said gear members, means for effecting rotation of the first two of said members of each set by power from said motor including worms constituting driving elements common to each set and rotating on vertical axes, and means connecting the others of said members in driving relation to said feed operating members.

107. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes extending longitudinally of the machine, two of which support coaxial gear members and another of which supports planet means meshing with said gear members, means for effecting rotation of two of said members of each set by power from said motor including worms constituting driving elements common to each set and rotating on vertical axes, and means connecting the others of said members in driving relation to said feed operating members.

108. In a mining machine, a motor, cutting mechanism driven thereby, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes extending longitudinally of the machine, two of which support coaxial gear members and another of which supports planet means meshing with said gear members, means for effecting rotation of the first two of said members of each set by power from said motor including worms constituting driving elements common to each set and rotating on vertical axes, and means connecting the others of said members in driving relation to said feed operating members.

109. In a mining machine, a horizontal motor, cutting mechanism driven thereby, and feeding means driven by the forward end of said motor comprising a worm rotatable on a vertical axis, and a cooperating differential mechanism.

110. In a mining machine, a horizontal motor, cutting mechanism driven thereby, and feeding means driven by the forward end of said motor comprising a worm rotatable on a vertical axis, and a plurality of cooperating differential mechanisms.

111. In a mining machine, a horizontal motor, cutting mechanism driven thereby, and feeding means driven by the forward end of said motor comprising a plurality of worms rotatable on vertical axes, and a plurality of cooperating differential mechanisms.
112. In a mining machine, a motor, cutting mechanism driven by the rear end of said motor, and feeding means driven wholly by the forward end of said motor and including a differential mechanism including a plurality of coaxial members and separate relatively rotatable driving elements for two of the same.
113. In a mining machine, a motor, cutting mechanism driven by the rear end of said motor, and feeding means driven wholly by the forward end of said motor and including a plurality of cooperating differential mechanisms.
114. In a mining machine, a motor, cutting mechanism driven by the rear end of said motor, and feeding means driven by the forward end of said motor and including a plurality of cooperating differential mechanisms arranged on parallel axes.
115. In a mining machine, a motor, cutting mechanism driven by the rear end of said motor, and feeding means driven by the forward end of said motor and including a plurality of cooperating differential mechanisms arranged on parallel longitudinally extending horizontal axes.
116. In a mining machine, a machine frame, a motor, cutting mechanism driven from the rear end of said motor including a forwardly projecting cutter bar rigidly secured within said frame and projecting therefrom, and feeding means driven by the forward end of said motor including a plurality of independently operable feed operating members.
117. In a mining machine, a machine frame, a motor, cutting mechanism driven from the rear end of said motor including a forwardly projecting cutter bar rigidly secured within said frame and projecting therefrom, and feeding means driven by the forward end of said motor including a plurality of independently operable feed operating members rotatable on parallel axes.
118. In a mining machine, a machine frame, a motor, cutting mechanism driven from the rear end of said motor including a forwardly projecting cutter bar rigidly secured within said frame and projecting therefrom, and feeding means driven by the forward end of said motor including a plurality of independently operable feed operating members rotatable on parallel longitudinally extending horizontal axes.
119. In a mining machine, a horizontal motor, cutting mechanism driven thereby, and feeding means driven by the forward
- end of said motor including a plurality of worms rotatable on vertical axes.
120. In a mining machine, a horizontal motor, cutting mechanism driven thereby, and feeding means driven by the forward end of said motor including a plurality of worms rotatable on vertical axes, and a plurality of worm gears cooperating therewith rotatable on horizontal axes.
121. In a room and pillar mining machine, a horizontal motor, cutting mechanism driven from the rear end of said motor and including a rigid forwardly projecting cutter bar, and feeding means driven by the forward end of said motor comprising a plurality of independently operable feed operating members.
122. In a room and pillar mining machine, a horizontal motor, cutting mechanism driven from the rear end of said motor and including a rigid forwardly projecting cutter bar, and feeding means driven by the forward end of said motor comprising a plurality of independently operable feed operating members rotating on parallel axes.
123. In a room and pillar mining machine, a horizontal motor, cutting mechanism driven from the rear end of said motor and including a rigid forwardly projecting cutter bar, and feeding means driven by the forward end of said motor comprising a plurality of independently operable feed operating members rotating on parallel longitudinally extending horizontal axes.
124. In a mining machine, the combination including feeding mechanism, a motor for actuating the same having a driving connection from one end thereof to said feeding mechanism, cutting mechanism also actuated by the motor driven from the other end of the latter and including a sprocket and a driving gear coaxial therewith, and truck driving mechanism driven by the gear.
125. In a mining machine, the combination including feeding mechanism at the forward end of a mining machine, a motor adjacent to and actuating said feeding mechanism, cutting mechanism including a cutter chain driving sprocket at the other side of the motor from the feeding mechanism, and truck driving mechanism driven by the cutting mechanism.
126. In a mining machine, the combination including feeding mechanism at the forward end of a mining machine, a motor adjacent to and actuating said feeding mechanism, cutting mechanism including a cutter chain driving sprocket at the other side of the motor from the feeding mechanism, and truck driving mechanism at the same end of the motor as the cutting mechanism.
127. In a mining machine, a motor dis-

posed longitudinally of said machine, cutting mechanism driven by the rear end of said motor, truck driving mechanism driven by the same end of said motor, and feeding means driven by the front end of said motor comprising a feed operating member, and means for transmitting power to said member including a plurality of coaxial members, two of which support coaxial gear members, and another of which supports planet means meshing with said gear members, means for effecting rotation of two of said members by power from said motor, and means connecting the other of said members in driving relation to said feed operating member.

128. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including a plurality of coaxial members, two of which support coaxial gear members and another of which supports planet means meshing with said gear members, means for effecting rotation of the first two of said members by power from said motor, and means connecting the other of said members in driving relation to said feed operating member.

129. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including a plurality of coaxial members rotating on horizontal axes, two of which support coaxial gear members and another of which supports planet means meshing with said gear members, means for effecting rotation of two of said members by power from said motor, and means connecting the other of said members in driving relation to said feed operating member.

130. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including a plurality of coaxial members rotating on horizontal axes, two of which support coaxial gear members and another of which supports planet means meshing with said gear members, means for effecting rotation of the first two of said members by power from said motor, and

means connecting the other of said members in driving relation to said feed operating member.

131. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including a plurality of coaxial members rotating on horizontal axes extending longitudinally of the machine, two of which support coaxial gear members and another of which supports planet means meshing with said gear members, means for effecting rotation of two of said members by power from said motor, and means connecting the other of said members in driving relation to said feed operating member.

132. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including a plurality of coaxial members rotating on horizontal axes extending longitudinally of the machine, two of which support coaxial gear members and another of which supports planet means meshing with said gear members, means for effecting rotation of the first two of said members by power from said motor, and means connecting the other of said members in driving relation to said feed operating member.

133. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members, two of which support coaxial gear members and another of which supports planet means meshing with said gear members, means for effecting rotation of two of said members of each set by power from said motor, and means connecting the others of said members in driving relation to said feed operating members.

134. In a mining machine, a motor disposed longitudinally of said machine, cutting mechanism driven by the rear end of said motor, truck driving mechanism driven by the same end of said motor, and feeding means driven by the front end of said motor comprising a plurality of feed operating

- members, and means for transmitting power to said members including a plurality of gearing units one individual to each of said members and each comprising a plurality of 5 coaxial members, two of which support coaxial gear members and another of which supports planet means meshing with said gear members, means for effecting rotation of the first two of said members of each set by power from 10 said motor, and means connecting the others of said members in driving relation to said feed operating members.
135. In a mining machine, a motor disposed longitudinally of said machine, cutting mechanism driven by the rear end of 15 said motor, truck driving mechanism driven by the same end of said motor, and feeding means driven by the front end of said motor comprising a plurality of feed operating 20 members, and means for transmitting power to said members including a plurality of gearing units one individual to each of said members and each comprising a plurality of coaxial members rotating on horizontal axes, 25 two of which support coaxial gear members and another of which supports planet means meshing with said gear members, means for effecting rotation of two of said members of each set by power from 30 said motor, and means connecting the others of said members in driving relation to said feed operating members.
136. In a mining machine, a motor disposed longitudinally of said machine, cutting mechanism driven by the rear end of 35 said motor, truck driving mechanism driven by the same end of said motor, and feeding means driven by the front end of said motor comprising a plurality of feed operating 40 members, and means for transmitting power to said members including a plurality of gearing units one individual to each of said members and each comprising a plurality of coaxial members rotating on horizontal 45 axes, two of which support coaxial gear members and another of which supports planet means meshing with said gear members, means for effecting rotation of the first 50 two of said members of each set by power from said motor, and means connecting the others of said members in driving relation to said feed operating members.
137. In a mining machine, a motor disposed longitudinally of said machine, cutting mechanism driven by the rear end of 55 said motor, truck driving mechanism driven by the same end of said motor, and feeding means driven by the front end of said motor comprising a plurality of feed operating 60 members, and means for transmitting power to said members including a plurality of gearing units one individual to each of said members and each comprising a plurality of coaxial members rotating on horizontal 65 axes extending longitudinally of the ma-
- chine, two of which support coaxial gear members and another of which supports planet means meshing with said gear members, means for effecting rotation of two of said members of each set by power from 70 said motor, and means connecting the others of said members in driving relation to said feed operating members.
138. In a mining machine, a motor disposed longitudinally of said machine, cutting mechanism driven by the rear end of 75 said motor, truck driving mechanism driven by the same end of said motor, and feeding means driven by the front end of said motor comprising a plurality of feed operating 80 members, and means for transmitting power to said members including a plurality of gearing units one individual to each of said members and each comprising a plurality of coaxial members rotating on horizontal axes 85 extending longitudinally of the machine, two of which support coaxial gear members and another of which supports planet means meshing with said gear members, means for effecting rotation of the first 90 two of said members of each set by power from said motor, and means connecting the others of said members in driving relation to said feed operating members.
139. In a mining machine, a motor disposed longitudinally of said machine, cutting mechanism driven by the rear end of 95 said motor, truck driving mechanism driven by the same end of said motor, and feeding means driven by the front end of said motor comprising a feed operating member, and means for transmitting power to said member including a plurality of coaxial members, two of which support coaxial gear members and another of which supports 100 planet means meshing with said gear members, means for effecting rotation of two of said members by power from said motor including worms driven from the front end 105 of the motor, and means connecting the other of said members in driving relation to said feed operating member.
140. In a mining machine, a motor disposed longitudinally of said machine, cutting mechanism driven by the rear end of 110 said motor, truck driving mechanism driven by the same end of said motor, and feeding means driven by the front end of said motor comprising a feed operating member, and means for transmitting power to said member including a plurality of coaxial members, two of which support coaxial gear members and another of which supports 115 planet means meshing with said gear members, means for effecting rotation of the first two of said members by power from said motor including worms driven from the front end 120 of the motor, and means connecting the other of said members in driving relation to said feed operating member.
141. In a mining machine, a motor disposed longitudinally of said machine, cutting mechanism driven by the rear end of 125 said motor, truck driving mechanism driven by the same end of said motor, and feeding means driven by the front end of said motor comprising a feed operating member, and means for transmitting power to said member including a plurality of coaxial members, two of which support coaxial gear members and another of which supports planet means meshing with said gear members, means for effecting rotation of the first two of said members by power from said motor including worms driven from the front end 130 of the motor, and means connecting the other of said members in driving relation to said feed operating member.

141. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including a plurality of coaxial members 5 rotating on horizontal axes, two of which support coaxial gear members and another of which supports planet means meshing with said gear members, means for effecting rotation of two of said members by power from said motor including worms driven from the front end of the motor, and means connecting the other of said members in driving relation to said feed operating member.
142. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including a plurality of coaxial members 10 rotating on horizontal axes, two of which support coaxial gear members and another of which supports planet means meshing with said gear members, means for effecting rotation of the first two of said members by power from said motor including worms driven from the front end of the motor, and means connecting the other of said members in driving relation to said feed operating member.
143. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including a plurality of coaxial members 15 rotating on horizontal axes extending longitudinally of the machine, two of which support coaxial gear members and another of which supports planet means meshing with said gear members, means for effecting rotation of two of said members by power from said motor including worms driven from the front end of the motor, and means connecting the other of said members in driving relation to said feed operating member.
144. In a mining machine, a motor disposed longitudinally of said machine, cutting mechanism driven by the rear end of said motor, truck driving mechanism driven by the same end of said motor, and feeding means driven by the front end of said motor comprising a feed operating member, 20 and means for transmitting power to said member including a plurality of coaxial gear members rotating on horizontal axes extending longitudinally of the machine, two of which support coaxial gear members and another of which supports planet means meshing with said gear members, means for effecting rotation of the first two of said members by power from said motor including worms driven from the front end of the motor, and means connecting the other of said members in driving relation to said feed operating member.
145. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members, two of which support coaxial gear members and another of which supports planet means meshing with said gear members, means for effecting rotation of two of said members of each set by power from said motor including worms driven from the front end of the motor, and means connecting the others of said members in driving relation to said feed operating members.
146. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members, two of which support coaxial gear members and another of which supports planet means meshing with said gear members, means for effecting rotation of the first two of said members of each set by power from said motor including worms driven from the front end of the motor, and means connecting the others of said members in driving relation to said feed operating members.
147. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members, two of which support coaxial gear members and another of which supports planet means meshing with said gear members, means for effecting rotation of the first two of said members of each set by power from said motor including worms driven from the front end of the motor, and means connecting the others of said members in driving relation to said feed operating members.

of coaxial members rotating on horizontal axes, two of which support coaxial gear members and another of which supports planet means meshing with said gear members, means for effecting rotation of two of said members of each set by power from said motor including worms driven from the front end of the motor, and means connecting the others of said members in driving relation to said feed operating members.

148. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members rotating on horizontal axes, two of which support coaxial gear members and another of which supports planet means meshing with said gear members, means for effecting rotation of the first two of said members of each set by power from said motor including worms driven from the front end of the motor, and means connecting the others of said members in driving relation to said feed operating members.

149. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members rotating on horizontal axes extending longitudinally of the machine, two of which support coaxial gear members and another of which supports planet means meshing with said gear members, means for effecting rotation of two of said members of each set by power from said motor including worms driven from the front end of the motor, and means connecting the others of said members in driving relation to said feed operating members.

150. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plural-

ity of coaxial members rotating on horizontal axes extending longitudinally of the machine, two of which support coaxial gear members and another of which supports planet means meshing with said gear members, means for effecting rotation of the first two of said members of each set by power from said motor including worms driven from the front end of the motor, and means connecting the others of said members in driving relation to said feed operating members.

151. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including a plurality of coaxial members, two of which support coaxial gear members and another of which supports planet means meshing with said gear members, means for effecting rotation of two of said members by power from said motor including worms rotating on parallel axes and driven from the front end of the motor, and means connecting the other of said members in driving relation to said feed operating member.

152. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including a plurality of coaxial members, two of which support coaxial gear members and another of which supports planet means meshing with said gear members, means for effecting rotation of the first two of said members by power from said motor including worms rotating on parallel axes and driven from the front end of the motor, and means connecting the other of said members in driving relation to said feed operating member.

153. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including a plurality of coaxial members rotating on horizontal axes, two of which support coaxial gear members and another of which supports planet means meshing with said gear members, means for effecting rotation of two of said members by power from said motor including worms rotating

on parallel axes and driven from the front end of the motor, and means connecting the other of said members in driving relation to said feed operating member.

posed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members, two of which support coaxial gear members and another of which supports planet means meshing with said gear members, means for effecting rotation of two of said members of each set by power from said motor including worms rotating on parallel axes and driven from the front end of the motor, and means connecting the others of said members in driving relation to said feed operating members.

158. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members, two of which support coaxial gear members and another of which supports planet means meshing with said gear members, means for effecting rotation of the first two of said members of each set by power from said motor including worms rotating on parallel axes and driven from the front end of the motor, and means connecting the others of said members in driving relation to said feed operating members. 100 105 110 115 120 125 130 135 140 145 150 155 160

159. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members rotating on horizontal axes, two of which support coaxial gear members and another of which supports planet means meshing with said gear members, means for effecting rotation of two of said members of each set by power from said motor including worms rotating on parallel axes and driven from the front end of the motor, and means connecting the others of said members in driving relation to said feed operating members.

160. In a mining machine, a motor dis- 130

- posed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members rotating on horizontal axes, two of which support coaxial gear members and another of which supports planet means meshing with said gear members, means for effecting rotation of the first two of said members of each set by power from said motor including worms rotating on parallel axes and driven from the front end of the motor, and means connecting the others of said members in driving relation to said feed operating members.
161. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members rotating on horizontal axes extending longitudinally of the machine, two of which support coaxial gear members and another of which supports planet means meshing with said gear members, means for effecting rotation of two of said members of each set by power from said motor including worms rotating on parallel axes and driven from the front end of the motor, and means connecting the others of said members in driving relation to said feed operating members.
162. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members rotating on horizontal axes extending longitudinally of the machine, two of which support coaxial gear members and another of which supports planet means meshing with said gear members, means for effecting rotation of the first two of said members of each set by power from said motor including worms rotating on parallel axes and driven from the front end of the motor, and means connecting the others of said members in driving relation to said feed operating members.
163. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including a plurality of coaxial members, two of which support coaxial gear members and another of which supports planet means meshing with said gear members, means for effecting rotation of two of said members by power from said motor including worms rotating on vertical axes and driven from the front end of the motor, and means connecting the other of said members in driving relation to said feed operating member.
164. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including a plurality of coaxial members, two of which support coaxial gear members and another of which supports planet means meshing with said gear members, means for effecting rotation of the first two of said members by power from said motor including worms rotating on vertical axes and driven from the front end of the motor, and means connecting the other of said members in driving relation to said feed operating member.
165. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including a plurality of coaxial members rotating on horizontal axes, two of which support coaxial gear members and another of which supports planet means meshing with said gear members, means for effecting rotation of two of said members by power from said motor including worms rotating on vertical axes and driven from the front end of the motor, and means connecting the other of said members in driving relation to said feed operating member.
166. In a mining machine, a motor disposed longitudinally of said machine, cutting mechanism driven by the rear end of said motor, truck driving mechanism driven by the same end of said motor, and feed-

ing means driven by the front end of said motor comprising a feed operating member, and means for transmitting power to said member including a plurality of coaxial members rotating on horizontal axes, two of which support coaxial gear members and another of which supports planet means meshing with said gear members, means for effecting rotation of the first two of said members by power from said motor including worms rotating on vertical axes and driven from the front end of the motor, and means connecting the other of said members in driving relation to said feed operating member.

167. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including a plurality of coaxial members rotating on horizontal axes extending longitudinally of the machine, two of which support coaxial gear members and another of which supports planet means meshing with said gear members, means for effecting rotation of two of said members by power from said motor including worms rotating on vertical axes and driven from the front end of the motor, and means connecting the other of said members in driving relation to said feed operating member.

168. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including a plurality of coaxial members rotating on horizontal axes extending longitudinally of the machine, two of which support coaxial gear members and another of which supports planet means meshing with said gear members, means for effecting rotation of the first two of said members by power from said motor including worms rotating on vertical axes and driven from the front end of the motor, and means connecting the other of said members in driving relation to said feed operating member.

169. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said

members and each comprising a plurality of coaxial members,

170. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members, two of which support coaxial gear members and another of which supports planet means meshing with said gear members, means for effecting rotation of the first two of said members of each set by power from said motor including worms rotating on vertical axes and driven from the front end of the motor, and means connecting the others of said members in driving relation to said feed operating members.

171. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members rotating on horizontal axes, two of which support coaxial gear members and another of which supports planet means meshing with said gear members, means for effecting rotation of two of said members of each set by power from said motor including worms rotating on vertical axes and driven from the front end of the motor, and means connecting the others of said members in driving relation to said feed operating members.

172. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members rotating on horizontal axes, two of which support coaxial gear members and another of which supports planet means meshing with said gear members, means for effecting rotation of the first two of said members of each set by power from said motor including worms rotating on vertical axes and driven from the front

end of the motor, and means connecting the others of said members in driving relation to said feed operating members.

173. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members rotating on horizontal axes extending longitudinally of the machine, two of which support coaxial gear members and another of which supports planet means meshing with said gear members, means for effecting rotation of two of said members of each set by power from said motor including worms rotating on vertical axes and driven from the front end of the motor, and means connecting the others of said members in driving relation to said feed operating members.

174. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of coaxial members rotating on horizontal axes extending longitudinally of the machine, two of which support coaxial gear members and another of which supports planet means meshing with said gear members, means for effecting rotation of the first two of said members of each set by power from said motor including worms rotating on vertical axes and driven from the front end of the motor, and means connecting the others of said members in driving relation to said feed operating members.

175. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members, two of which support coaxial gear members and another of which supports planet means meshing with said gear members, means for effecting rotation of two of said members of each set by power from said

motor including worms constituting driving elements common to each set and rotating on vertical axes, and means connecting the others of said members in driving relation to said feed operating members.

176. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of coaxial members, two of which support coaxial gear members and another of which supports planet means meshing with said gear members, means for effecting rotation of the first two of said members of each set by power from said motor including worms constituting driving elements common to each set and rotating on vertical axes, and means connecting the others of said members in driving relation to said feed operating members.

177. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of coaxial members rotating on horizontal axes, two of which support coaxial gear members and another of which supports planet means meshing with said gear members, means for effecting rotation of two of said members of each set by power from said motor including worms constituting driving elements common to each set and rotating on vertical axes, and means connecting the others of said members in driving relation to said feed operating members.

178. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members rotating on horizontal axes, two of which support coaxial gear members and another of which supports planet means meshing with said gear members, means for effecting rotation of the first two of said

members of each set by power from said motor including worms constituting driving elements common to each set and rotating on vertical axes, and means connecting the others of said members in driving relation to said feed operating members.

179. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members rotating on horizontal axes extending longitudinally of the machine, two of which support coaxial gear members and another of which supports planet means meshing with said gear members, means for effecting rotation of two of said members of each set by power from said motor including worms constituting driving elements common to each set and rotating on vertical axes, and means connecting the others of said members in driving relation to said feed operating members.

180. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to each of said members and each comprising a plurality of coaxial members rotating on horizontal axes extending longitudinally of the machine, two of which support coaxial gear members and another of which supports planet means meshing with said gear members, means for effecting rotation of the first two of said members by power from said motor including worms constituting driving elements common to each set and rotating on vertical axes, and means connecting the others of said members in driving relation to said feed operating members.

181. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including in coaxial relation therewith a plurality of coaxial members, two of which support coaxial gear members and another of which supports planet means meshing with said gear members, means for effecting

rotation of two of said members by power from said motor, and means connecting the other of said members in driving relation to said feed operating member.

182. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including in coaxial relation therewith a plurality of coaxial members, two of which support coaxial gear members and another of which supports planet means meshing with said gear members, means for effecting rotation of the first two of said members by power from said motor, and means connecting the other of said members in driving relation to said feed operating member.

183. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including in coaxial relation therewith a plurality of coaxial members rotating on horizontal axes, two of which support coaxial gear members and another of which supports planet means meshing with said gear members, means for effecting rotation of two of said members by power from said motor, and means connecting the other of said members in driving relation to said feed operating member.

184. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including in coaxial relation therewith a plurality of coaxial members rotating on horizontal axes, two of which support coaxial gear members and another of which supports planet means meshing with said gear members, means for effecting rotation of the first two of said members by power from said motor, and means connecting the other of said members in driving relation to said feed operating member.

185. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said mem-

ber including in coaxial relation therewith a plurality of coaxial members rotating on horizontal axes extending longitudinally of the machine, two of which support coaxial gear members and another of which supports planet means meshing with said gear members, means for effecting rotation of two of said members by power from said motor, and means connecting the other of said members in driving relation to said feed operating members.

186. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including in coaxial relation therewith a plurality of coaxial members rotating on horizontal axes extending longitudinally of the machine, two of which support coaxial gear members and another of which supports planet means meshing with said gear members, means for effecting rotation of the first two of said members by power from said motor, and means connecting the other of said members in driving relation to said feed operating member.

187. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to and coaxial with each of said members and each comprising a plurality of coaxial members, two of which support coaxial gear members and another of which supports planet means meshing with said gear members, means for effecting rotation of two of said members of each set by power from said motor, and means connecting the others of said members in driving relation to said feed operating members.

188. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to and coaxial with each of said members and each comprising a plurality of coaxial members, two of which support coaxial gear members and another of which supports planet means meshing with said gear members, means for effecting rotation of two of said members of each set by power from said motor, and means connecting the others of said members in driv-

ing relation of the first two of said members of each set by power from said motor, and means connecting the others of said members in driving relation to said feed operating members.

189. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes, two of which support coaxial gear members and another of which supports planet means meshing with said gear members, means for effecting rotation of two of said members of each set by power from said motor, and means connecting the others of said members in driving relation to said feed operating members.

190. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes, two of which support coaxial gear members and another of which supports planet means meshing with said gear members, means for effecting rotation of the first two of said members of each set by power from said motor, and means connecting the others of said members in driving relation to said feed operating members.

191. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes extending longitudinally of the machine, two of which support coaxial gear members and another of which supports planet means meshing with said gear members, means for effecting rotation of two of said members of each set by power from said motor, and means connecting the others of said members in driv-

ing relation to said feed operating members.

192. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes extending longitudinally of the machine, two of which support coaxial gear members and another of which supports planet means meshing with said gear members, means for effecting rotation of the first two of said members of each set by power from said motor, and means connecting the others of said members in driving relation to said feed operating members.

193. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including in coaxial relation therewith a plurality of coaxial members, two of which support coaxial gear members and another of which supports planet means meshing with said gear members, means for effecting rotation of two of said members by power from said motor including worms driven from the front end of the motor, and means connecting the other of said members in driving relation to said feed operating member.

194. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including in coaxial relation therewith a plurality of coaxial members, two of which support coaxial gear members and another of which supports planet means meshing with said gear members, means for effecting rotation of the first two of said members by power from said motor including worms driven from the front end of the motor, and means connecting the other of said members in driving relation to said feed operating member.

195. In a mining machine, a motor disposed longitudinally of said machine, cutting mechanism driven by the rear end of said motor, truck driving mechanism driven

by the same end of said motor, and feeding means driven by the front end of said motor comprising a feed operating member, and means for transmitting power to said member including coaxial therewith a plurality of coaxial members rotating on horizontal axes, two of which support coaxial gear members and another of which supports planet means meshing with said gear members, means for effecting rotation of two of said members by power from said motor including worms driven from the front end of the motor, and means connecting the other of said members in driving relation to said feed operating member.

196. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including coaxial therewith a plurality of coaxial members rotating on horizontal axes, two of which support coaxial gear members and another of which supports planet means meshing with said gear members, means for effecting rotation of the first two of said members by power from said motor including worms driven from the front end of the motor, and means connecting the other of said members in driving relation to said feed operating member.

197. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including coaxial therewith a plurality of coaxial members rotating on horizontal axes extending longitudinally of the machine, two of which support coaxial gear members and another of which supports planet means meshing with said gear members, means for effecting rotation of two of said members by power from said motor including worms driven from the front end of the motor, and means connecting the other of said members in driving relation to said feed operating member.

198. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including coaxial therewith a plurality of coaxial members rotating on horizontal axes extending longitudinally of the ma-

tating on horizontal axes extending longitudinally of the machine, two of which support coaxial gear members and another of which supports planet means meshing with said gear members, means for effecting rotation of the first two of said members of each set by power from said motor including worms driven from the front end of the motor, and means connecting the others of said members in driving relation to said feed operating members.

205. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including coaxial therewith a plurality of coaxial members, two of which support coaxial gear members and another of which supports planet means meshing with said gear members, means for effecting rotation of two of said members by power from said motor including worms rotating on parallel axes and driven from the front end of the motor, and means connecting the other of said members in driving relation to said feed operating member.

206. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including coaxial therewith a plurality of coaxial members, two of which support coaxial gear members and another of which supports planet means meshing with said gear members, means for effecting rotation of the first two of said members by power from said motor including worms rotating on parallel axes and driven from the front end of the motor, and means connecting the other of said members in driving relation to said feed operating member.

207. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including coaxial therewith a plurality of coaxial members rotating on horizontal axes, two of which support coaxial gear members and another of which supports planet means meshing with said gear members, means for effecting rotation of two of said members by power from said motor including worms rotating on parallel axes and driven from

the front end of the motor, and means connecting the other of said members in driving relation to said feed operating member.

208. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including coaxial therewith a plurality of coaxial members rotating on horizontal axes, two of which support coaxial gear members and another of which supports planet means meshing with said gear members, means for effecting rotation of the first two of said members by power from said motor including worms rotating on parallel axes and driven from the front end of the motor, and means connecting the other of said members in driving relation to said feed operating member.

209. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including coaxial therewith a plurality of coaxial members rotating on horizontal axes extending longitudinally of the machine, two of which support coaxial gear members and another of which supports planet means meshing with said gear members, means for effecting rotation of two of said members by power from said motor including worms rotating on parallel axes and driven from the front end of the motor, and means connecting the other of said members in driving relation to said feed operating member.

210. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including coaxial therewith a plurality of coaxial members rotating on horizontal axes extending longitudinally of the machine, two of which support coaxial gear members and another of which supports planet means meshing with said gear members, means for effecting rotation of the first two of said members by power from said motor including worms rotating on parallel axes and driven from the front end of the motor, and means connecting the other of said members in driving relation to said feed operating member.

211. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of 10 gearing units one individual to and coaxial with each of said members and each comprising a plurality of coaxial members, two of which support coaxial gear members and another of which supports planet means meshing with said gear members, means for effecting rotation of two of said members of each set by power from said motor including worms rotating on parallel axes and driven from the front end of the motor, and 15 means connecting the others of said members in driving relation to said feed operating member.

212. In a mining machine, a motor disposed longitudinally of said machine, cutting mechanism driven by the rear end of said motor, truck driving mechanism driven by the same end of said motor, and feeding means driven by the front end of said motor comprising a plurality of feed operating 20 members, and means for transmitting power to said members including a plurality of gearing units one individual to and coaxial with each of said members and each comprising a plurality of coaxial members, two of which support coaxial gear members and another of which supports planet means meshing with said gear members, means for effecting rotation of the first two of said 25 members of each set by power from said motor including worms rotating on parallel axes and driven from the front end of the motor, and means connecting the others of said members in driving relation to said feed operating members.

213. In a mining machine, a motor disposed longitudinally of said machine, cutting mechanism driven by the rear end of said motor, truck driving mechanism driven by the same end of said motor, and feeding 30 means driven by the front end of said motor comprising a plurality of feed operating members, and means for transmitting power to said members including a plurality of gearing units one individual to and coaxial with each of said members and each comprising a plurality of coaxial members rotating on horizontal axes, two of which support coaxial gear members and another of which supports planet means meshing with 35 said gear members, means for effecting rotation of two of said members of each set by power from said motor including worms rotating on parallel axes and driven from the front end of the motor, and means connecting the others of said members in driv- 40

ing relation to said feed operating members.

214. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of 45 gearing units one individual to and coaxial with each of said members and each comprising a plurality of coaxial members rotating on horizontal axes, two of which support coaxial gear members and another of which supports planet means meshing with 50 said gear members, means for effecting rotation of the first two of said members of each set by power from said motor including worms rotating on parallel axes and driven from the front end of the motor, and means connecting the others of said members in driving relation to said feed operating members.

215. In a mining machine, a motor disposed longitudinally of said machine, cutting mechanism driven by the rear end of said motor, truck driving mechanism driven by the same end of said motor, and feeding means driven by the front end of said motor comprising a plurality of feed operating 55 members, and means for transmitting power to said members including a plurality of gearing units one individual to and coaxial with each of said members and each comprising a plurality of coaxial members rotating on horizontal axes extending longitudinally of the machine, two of which support coaxial gear members and another of which supports planet means meshing with 60 said gear members, means for effecting rotation of two of said members of each set by power from said motor including worms rotating on parallel axes and driven from the front end of the motor, and means connecting the others of said members in driving relation to said feed operating members.

216. In a mining machine, a motor disposed longitudinally of said machine, cutting mechanism driven by the rear end of said motor, truck driving mechanism driven by the same end of said motor, and feeding means driven by the front end of said motor comprising a plurality of feed operating 65 members, and means for transmitting power to said members including a plurality of gearing units one individual to and coaxial with each of said members and each comprising a plurality of coaxial members rotating on horizontal axes extending longitudinally of the machine, two of which support coaxial gear members and another of which supports planet means meshing with 70 said gear members, means for effecting rotation of the first two of said members of each set by power from said motor including worms rotating on parallel axes and driven from the front end of the motor, and means connecting the others of said members in driv- 75

each set by power from said motor including worms rotating on parallel axes and driven from the front end of the motor, and means connecting the others of said members in driving relation to said feed operating members.

217. In a mining machine, a motor disposed longitudinally of said machine, cutting mechanism driven by the rear end of
10 said motor, truck driving mechanism driven by the same end of said motor, and feeding means driven by the front end of said motor comprising a feed operating member, and means for transmitting power to said member including coaxial therewith a plurality of coaxial members, two of which support coaxial gear members and another of which supports planet means meshing with said gear members, means for effecting rotation
15 of two of said members by power from said motor including worms rotating on vertical axes and driven from the front end of the motor, and means connecting the other of said members in driving relation to said
20 feed operating members.

218. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including coaxial therewith a plurality of coaxial members, two of which support coaxial gear members and another of which supports planet means meshing with said gear members, means for effecting rotation of the first two of said members by power from said motor including worms rotating on vertical axes and driven from the front end of the motor, and means connecting the other of said members in driving relation to said feed operating member.

45 219. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including coaxial therewith a plurality of coaxial members rotating on horizontal axes, two of which support coaxial gear members and another of which supports planet means meshing with said gear members, means for effecting rotation of two of said members by power from said motor including worms rotating on vertical axes and driven from the front end of the motor and means connecting the other of said members in driving relation to said feed operating member.

65 220. In a mining machine, a motor dis-

posed longitudinally of said machine, cutting mechanism driven by the rear end of said motor, truck driving mechanism driven by the same end of said motor, and feeding means driven by the front end of said motor comprising a feed operating member, and means for transmitting power to said member including coaxial therewith a plurality of coaxial members rotating on horizontal axes, two of which support coaxial gear members and another of which supports planet means meshing with said gear members, means for effecting rotation of the first two of said members by power from said motor including worms rotating on vertical axes and driven from the front end of the motor, and means connecting the other of said members in driving relation to said feed operating member.

221. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including coaxial therewith a plurality of coaxial members rotating on horizontal axes extending longitudinally of the machine, two of which support coaxial gear members and another of which supports planet means meshing with said gear members, means for effecting rotation of two of said members by power from said motor including worms rotating on vertical axes and driven from the front end of the motor, and means connecting the other of said members in driving relation to said feed operating member.

222. In a mining machine, a motor disposed longitudinally of said machine, cutting mechanism driven by the rear end of said motor, truck driving mechanism driven by the same end of said motor, and feeding means driven by the front end of said motor comprising a feed operating member, and means for transmitting power to said member including coaxial therewith a plurality of coaxial members rotating on horizontal axes extending longitudinally of the machine, two of which support coaxial gear members and another of which supports planet means meshing with said gear members, means for effecting rotation of the first two of said members by power from said motor including worms rotating on vertical axes and driven from the front end of the motor, and means connecting the other of said members in driving relation to said feed operating member. 110 115 120 125

223. In a mining machine, a motor disposed longitudinally of said machine, cutting mechanism driven by the rear end of said motor, truck driving mechanism driven 130

by the same end of said motor, and feeding means driven by the front end of said motor comprising a plurality of feed operating members, and means for transmitting power to said members including a plurality of gearing units one individual to and coaxial with each of said members and each comprising a plurality of coaxial members, two of which support coaxial gear members and another of which supports planet means meshing with said gear members, means for effecting rotation of two of said members of each set by power from said motor including worms rotating on vertical axes and driven from the front end of the motor, and means connecting the others of said members in driving relation to said feed operating members.

224. In a mining machine, a motor disposed longitudinally of said machine, cut

227. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes extending longitudinally of the machine, two of which support coaxial gear members and another of which supports planet means meshing with said gear members, means for effecting rotation of two of said members of each set by power from said motor including worms rotating on vertical axes and driven from the 90 95 100 105

65 226. In a mining machine, a motor disposed longitudinally of said machine, cutting mechanism driven by the rear end of each set by power from said motor including worms rotating on vertical axes and driven from the front end of the motor, and means connecting the others of said members in 130

- driven relation to said feed operating members.
229. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to and coaxial with each of said members and each comprising a plurality of coaxial members, two of which support coaxial gear members and another of which supports planet means meshing with said gear members, means for effecting rotation of two of said members of each set by power from said motor including worms constituting driving elements common to each set and rotating on vertical axes, and means connecting the others of said members in driving relation to said feed operating members.
230. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to and coaxial with each of said members and each comprising a plurality of coaxial members, two of which support coaxial gear members and another of which supports planet means meshing with said gear members, means for effecting rotation of the first two of said members of each set by power from said motor including worms constituting driving elements common to each set and rotating on vertical axes, and means connecting the others of said members in driving relation to said feed operating members.
231. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes, two of which support coaxial gear members and another of which supports planet means meshing with said gear members, means for effecting rotation of two of said members of each set by power from said motor including worms constituting driving elements common to each set and rotating on vertical axes, and means connecting the others of said members in driving relation to said feed operating members.
232. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes, two of which support coaxial gear members and another of which supports planet means meshing with said gear members, means for effecting rotation of the first two of said members of each set by power from said motor including worms constituting driving elements common to each set and rotating on vertical axes, and means connecting the others of said members in driving relation to said feed operating members.
233. In a mining machine, a motor disposed longitudinally of said machine, cutting mechanism driven by the rear end of said motor, truck driving mechanism driven by the same end of said motor, and feeding means driven by the front end of said motor comprising a plurality of feed operating members, and means for transmitting power to said members including a plurality of gearing units one individual to and coaxial with each of said members and each comprising a plurality of coaxial members rotating on horizontal axes extending longitudinally of the machine, two of which support coaxial gear members and another of which supports planet means meshing with said gear members, means for effecting rotation of two of said members of each set by power from said motor including worms constituting driving elements common to each set and rotating on vertical axes, and means connecting the others of said members in driving relation to said feed operating members.
234. In a mining machine, a machine frame slidable on its bottom on the mine bottom, a motor on said frame, cutting mechanism driven by said motor including a rigid cutter bar extending forwardly lengthwise of said frame, and feeding means driven by said motor including a feed operating member and a takeup member each being adapted to cooperate with flexible feeding means and disposed at the forward end of said frame, said members being rotatable on axes extending longitudinally of said frame.

In testimony whereof I affix my signature,

CHARLES F. OSGOOD.

130

CERTIFICATE OF CORRECTION.

Patent No. 1,662,798.

Granted March 13, 1928, to

CHARLES F. OSGOOD.

It is hereby certified that error appears in the printed specification of the above numbered patent requiring correction as follows: Page 4, line 51, claim 3, strike out the article "a" third occurrence; page 11, line 3, claim 52, for the misspelled word "pluraltiy" read "plurality"; page 14, line 94, claim 79, after the word "of" insert the word "said"; page 19, lines 95 and 96, claim 123, for "projecing" read "projecting"; page 23, line 86, claim 151, for "pluraliy" read "plurality", and line 100, claim 152, after the word "driven" strike out the comma; page 31, line 103, claim 203, for "tarnsmitting" read "transmitting"; page 32, line 26, claim 205, for "ineculding" read "including"; and that the said Letters Patent should be read with these corrections therein that the same may conform to the record of the case in the Patent Office.

Signed and sealed this 10th day of April, A. D. 1928.

(Seal)

M. J. Moore,
Acting Commissioner of Patents.
